US0D1013735S

(12) **United States Design Patent** (10) Patent No.: **US D1,013,735 S**
(45) Date of Patent: ** Feb. 6, 2024

(54) **MOVABLE BARRIER OPERATOR**

(71) Applicant: **The Chamberlain Group LLC**, Oak Brook, IL (US)

(72) Inventors: **Jeremy Abel**, West Dundee, IL (US); **Matthew James Baer**, Forest Park, IL (US)

(73) Assignee: **THE CHAMBERLAIN GROUP LLC**, Oak Brook, IL (US)

(**) Term: **15 Years**

(21) Appl. No.: **29/725,280**

(22) Filed: **Feb. 24, 2020**

(51) LOC (14) Cl. **15-09**

(52) U.S. Cl.

USPC **D15/148**; D15/199; D13/168

(58) **Field of Classification Search**

(57) **CLAIM**

We claim the ornamental design for a movable barrier operator, as shown and described.

DESCRIPTION

FIG. 1 is a first perspective view of a movable barrier operator in accordance with a first embodiment of our new design;

FIG. 2 is a second perspective view of the movable barrier operator;

FIG. 3 is a bottom plan view of the movable barrier operator;

FIG. 4 is a top plan view of the movable barrier operator;

FIG. 5 is a first end elevation view of the movable barrier operator;

FIG. 6 is a second end elevation view of the movable barrier operator;

FIG. 7 is a first side elevation view of the movable barrier operator; and,

FIG. 8 is a second side elevation view of the movable barrier operator.

Broken lines in the drawings form no part of the claimed design.

1 Claim, 4 Drawing Sheets
